DESIGN FOR A SUBMARINE TANK

Chinneth Hill, Victoria, Va.

Application September 9, 1944, Serial No. 115,244

Term of patent 7 years

(Cl. D14—3)

To all whom it may concern:

Be it known that I, Chinneth Hill, a citizen of the United States, residing at Victoria, in the county of Lunenburg and State of Virginia, have invented a new, original, and ornamental Design for a Submarine Tank, of which the following is a specification, reference being had to the accompanying drawing, forming part thereof.

In the drawing:

Fig. 1 is a plan view of a submarine tank, showing my new design;

Fig. 2 is a side elevational view.

Fig. 3 is a front elevational view of the submarine tank.

I claim:

The ornamental design for a submarine tank, as shown.

CHINNETH HILL.
